Primary Examiner — Melanie H Tung(74) *Attorney, Agent, or Firm* — Kilpatrick Townsend & Stockton LLP(57) **CLAIM**

The ornamental design for a display screen or portion thereof with graphical user interface, as shown and described.

DESCRIPTION

The single FIGURE is a front view of a display screen or portion thereof with graphical user interface showing our new design.

The broken line showing of a display screen or portion thereof is for illustrative purposes only and forms no part of the claimed design.

1 Claim, 1 Drawing Sheet(56)
